US00D981795S

(12) **United States Design Patent** (10) **Patent No.:** **US D981,795 S**
(45) **Date of Patent:** **** Mar. 28, 2023**

(54) **FOOD CONTAINER LIDS HOLDER**

(71) Applicant: **XIAMEN LEGENDA ELECTRONIC TECHNOLOGY COMPANY LIMITED**, Xiamen (CN)

(72) Inventor: **Wenda Zhong**, Xiamen (CN)

(73) Assignee: **XIAMEN LEGENDA ELECTRONIC TECHNOLOGY COMPANY LIMITED**, Xiamen (CN)

(**) Term: **15 Years**

(21) Appl. No.: **29/804,929**

(22) Filed: **Aug. 24, 2021**

(30) **Foreign Application Priority Data**

Feb. 26, 2021 (CN) 202130109505.2

(51) **LOC (14) Cl.** **07-09**

(52) **U.S. Cl.**

USPC **D7/601**

(57) **CLAIM**

The ornamental design for a food container lids holder, as shown and described.

DESCRIPTION

FIG. 1 is a top perspective view of a food container lids holder showing my new design;

FIG. 2 is a top view thereof;

FIG. 3 is a bottom view thereof;

FIG. 4 is a right side view thereof;

FIG. 5 is a left side view thereof;

FIG. 6 is a front view thereof, a rear view being a mirror image of the front view;

FIG. 7 is a bottom perspective view thereof;

FIG. 8 is a bottom perspective view thereof, shown in an extended configuration of use;

FIG. 9 is a top perspective view thereof, shown in an extended configuration of use with partitions; and,

FIG. 10 is a top perspective view thereof, shown with partitions.

The broken lines in the drawings illustrate partitions and represent environmental structure that forms no part of the claimed design.

1 Claim, 10 Drawing Sheets
